CLAIM

The ornamental design for a video camera with video tape recorder, as shown and described.

DESCRIPTION

FIG. 1 is a perspective view of the rear, top and right side of a video camera with video tape recorder showing our new design;

FIG. 2 is a perspective view of the top, front and right side thereof;

FIG. 3 is a top plan view thereof;

FIG. 4 is a right side elevational view thereof;

FIG. 5 is a front elevational view thereof;

FIG. 6 is a rear elevational view thereof;

FIG. 7 is a left side elevational view thereof;

FIG. 8 is a bottom plan view thereof; and,

FIG. 9 is a perspective view similar to FIG. 2 with the eye piece pivoted to a forward position.
